SNAP ACTING MECHANISM

James P. Watson, Inglewood, Calif.

(59 Waterway Road, Waterway Village, Jupiter, Fla.)

Filed Mar. 10, 1958, Ser. No. 720,303

10 Claims. (Cl. 200—67)

This invention relates to bi-stable mechanisms and particularly to a bi-stable electric switch.

It is an object of this invention to provide a bi-stable or snap acting mechanism employing fewer parts than heretofore required to achieve the same results.

It is another object of this invention to provide such a mechanism which is simple in design, not only in assembly but also in components, whereby punch-press manufacture of components may be effected.

It is a further object of this invention to provide a bi-stable mechanism and particularly a bi-stable switch wherein a given current capacity may be effected in a smaller size.

It is another object of this invention to provide a bi-stable mechanism wherein the operating travel and pressure are adjustable. This is particularly advantageous in that adjustment may be employed at the factory to compensate for manufacturing tolerances. The adjustments may be also used by the customer to adapt the switch to various actuating mechanisms or devices.

It is another object of this invention to provide a high current capacity in a bi-stable or snap acting switch having a very small body.

It is another object of this invention to provide a bi-stable mechanism having long life, minimum bounce or rebound, and high vibration resistance.

It is another object of this invention to provide a bi-stable or snap acting switch well adapted for plug-in use whereby it may be readily employed with printed circuits.

Yet another object of this invention is to provide new and improved mounting means for mounting a mechanism or a plurality of stacked mechanisms of the character described firmly and securely on a wall, panel or the like.

A further object of this invention is to provide new and improved mounting means for mounting such mechanisms which provides resilient pressure at advantageous points of the mechanism to afford greater stability in the mounting and elimination of vibration or looseness therein without distortion of the housing or the mechanism.

In accordance with these and other objects which will become apparent hereinafter, preferred forms of the present invention will now be described with reference to the accompanying drawings wherein:

FIG. 1 is a longitudinal sectional view of one form of the present invention;

FIG. 2 is a longitudinal section taken at right angles to FIG. 1 along the line 2—2 of FIG. 1;

FIG. 3 is an end view looking from the right in FIG. 2.

FIG. 4 is a view similar to FIG. 3, with the end cap removed;

FIG. 5 is a fragmentary perspective showing the resilient bi-stable leaf forming a component of the assembly shown in FIGS. 1 and 2;

FIG. 6 is a fragmentary longitudinal section of another form of the present invention, the remainder of the mech-

2

anism being substantially the same as in the first form except for the shape of the case;

FIG. 7 is a longitudinal section taken on line 7—7 in FIG. 6;

FIG. 8 is a cross-section taken on line 8—8 in FIG. 7;

FIG. 9 is an exploded perspective view showing the resilient bi-stable leaf member and the cage or frame in which it is compressed and pivoted;

FIG. 10 is a fragmentary top view partially sectioned of still another rectangular form of the present invention, the remainder of the mechanism being substantially the same as the first form except for the shape of the case;

FIG. 11 is a longitudinal section taken at right angles to FIG. 10;

FIG. 12 is a fragmentary sectional view of still another form of the present invention;

FIG. 13 is a section taken on line 13—13 of FIG. 12;

FIG. 14 is a fragmentary section of still another form of the present invention;

FIG. 15 is an exploded perspective view of a portion of the resilient bi-stable leaf of FIG. 14;

FIG. 16 is a view of the leaf assembled and turned over from the position shown in FIG. 15;

FIG. 17 is an exploded partial view of another form of leaf member at the operating pivot point thereof;

FIG. 18 is a view similar to FIG. 17 showing the portions assembled together;

FIG. 19 is a fragmentary section showing the method of pivoting the leaf of FIG. 18;

FIG. 20 is an enlarged fragmentary view similar to FIG. 19;

FIG. 21 is a schematic diagram, in graph form, illustrating the relation of the length of the leaf to the contact pressure and operating travel;

FIG. 22 is a perspective view, in elevation, illustrating a further modified embodiment of this invention;

FIG. 23 is a perspective view, in elevation, illustrating a mounting clip adapted to mount the latter embodiment in a panel or the like;

FIG. 24 is an enlarged fragmentary side view thereof with parts broken away, illustrating the latter embodiment as installed in the panel;

FIG. 25 is a fragmentary horizontal cross-sectional view, with parts shown in elevation, as taken along line 25—25 of FIG. 24;

FIG. 26 is a view similar to FIG. 24, of a further embodiment of this invention;

FIG. 27 is an exploded view, in perspective, of a mounting means for mounting a switch of the type illustrated in FIGS. 6—8 to a panel or the like;

FIG. 28 is an end view, in elevation, illustrating the preliminary step in the installation thereof;

FIG. 29 is an end view similar to FIG. 28, illustrating the finished installation thereof; and

FIG. 30 is an end view similar to FIGS. 28 and 29, illustrating installation of a plurality of the latter switches.

Referring to the drawings, there is shown, in FIG. 1, a bi-stable mechanism housed in a cylindrical case or housing 21 preferably made of rigid insulating material. To the left end of the cylindrical casing 21 is shown formed as an integral wall 22 while the right end of the casing is closed by a cap 23 made of pliant resilient material. Mounted within the housing 21 is a rigid gen-

erally U-shaped frame or cage 24, having a pair of generally parallel arms 26 and 27. The bight portion of the U-shaped frame 24 is elongate and lies parallel with the case 21, while the arms 26 and 27 are disposed transversely thereof.

Spanning the arms 26 and 27 and generally paralleling the bight of the U-frame 24, is a bi-stable resilient leaf 28 made of springy metal, preferably having substantially the same coefficient of thermal expansion of frame 24. The arm 26 has a pivot means 29 for pivoting the left end of the spring 28 and the arm 27 has a pivot means 31 for pivoting the right end of the spring 28.

The pivot means 29 comprises a groove 32 formed in the inner face of the arm 26 in which rides the left end of the leaf 28 capped by a sheath 33 doubled over the left end of the spring 28 as shown in FIG. 5. The sheath 33 forms the actual bearing surface between the leaf 28 and the groove 32.

At its right end, the leaf 28 is laterally ensmalled, as shown in FIG. 5, to form a pair of shoulders 34, one at each side of the leaf 28. Between the shoulders 34 the leaf 28 continues integrally to the right and is bent downward at right angles to form an arm 36, and thence is bent back in serpentine fashion as shown at 15 37 and is anchored to a tab 38, extending from the frame 24, being bonded thereto at 39. Thus a single integral structure extends from the sheath 33 around to the bond 39.

That portion of the leaf which is continued beyond and to the right of the pivot means 31 is stiffened by an envelope 41 which has a pair of outwardly extending wings 42 sheathing the shoulders 34 and forming a bearing surface with the bottom of a groove 43 formed on the inside face of the frame arm 27. To accommodate the continued portion 36 of the leaf 28 a notch 45 is cut out of the arm 27. The transverse portion of the envelope 41 has a longitudinal ridge 44 to provide an infinite number of pressure points for an operating boss to be described hereinafter.

The normal unstressed length of that portion of the leaf spring 28 between the bearing or sheath members 33 and 42 is slightly greater than the distance between the grooves 32 and 43, so that the leaf 28 is forced to bow either upward or downward and is biased in bi-stable fashion either to its upper or lower attitude by the natural resiliency and stiffness of the leaf. The stiffness of the serpentine portion 37 biases the lower end of the transverse portion 36 to the right (FIG. 2) thereby biasing the leaf 28 to the lower of its two stable positions, as shown in FIG. 2.

The radiused bearing surfaces formed by the sheaths at 33 and 42 serve to prevent undue abrasion and wear of their respective grooves.

The length-to-thickness ratio of the leaf spring 28 is important to successful operation. If the leaf is too rigid, separation of contact from terminal may occur prior to snap-over. If the leaf is too flexible, the switch becomes more sensitive to vibration.

It has been found that in using a #10 alloy of beryllium copper, in full hard condition and of .005 inch thickness, the most satisfactory range of lengths lies between .600 and .800 inch.

As exemplified in the graph of FIG. 21, in a leaf spring of such alloy and thickness, indicated by the line A, having a length of .625 inch, an arch .035 inch high and .125 inch in diameter, contacts centered .105 inch from the idling pivot, such as the end 33 in the groove 32, the contact pressure is 7.2 oz., rising to 11 oz., at the moment of snap-over indicated at A'. Line B represents a leaf identical to spring A with the exception that its length is .700 inch, the contact pressure is 6.2 oz. rising to 12.8 oz., and subsequently decreasing to 12 oz. at the snapover moment B'. A leaf denoted by C, having a length of .800 inch, has a contact pressure of 5.2 oz.,

rising to 12.2 oz., at which pressure the snapover, indicated at C', occurs.

A wave is advantageously formed in the spring during its flexing and prior to the snapover. The wave tends to increase pressure at the contact point until the snapover occurs, thus providing a firm electrical contact at the terminal until the snapover occurs.

The width of leaf will vary with the size of contact required. The contacts should be placed as near the idling pivot as contact gap requirements will allow. This places the contact mass nearer a point of support and allows more length of leaf from the operating pivot to the contact in which to form the wave, which is so important to maintaining firm contact until snapover occurs.

Since the stiffness of a flat leaf spring varies approximately as the cube of the thickness, and other factors such as hardness and type of material also affect this value, the length-to-thickness ratio will change for each type and thickness of material selected.

To actuate the mechanism an operating means or member is provided for engaging the stiffened portion 36 of the leaf 28 and pressing it against the bias of the spring 37 into its upper position shown in phantom in FIG. 2. In the forms shown in FIGS. 1-5 this operating member consists of the cap 23 which is formed as a disc mounted for rotatable adjustment over the open end of the housing 21 by means of an inward bead 47 riding in a circumferential groove 48 formed in the housing 21. The cap 23 is mounted concentrically of the axis of the housing 21. Formed integral on the inner face of the cap 23 is a circular boss 49 disposed eccentrically of the axis of the housing 21. The boss 49 engages the ridge 44 of arm or extended portion 36 to actuate the leaf 28. The cap 23 is thickened in the center so as to be sufficiently rigid to transmit the operating force from the exterior of the cap to the arm 36, while still pliant enough to allow the cap 23 to be pushed inwardly, thereby operating the arm 36 through the intermediacy of the boss 49. To enhance the flexibility of the cap 23 for operating purposes, an annular corrugation 51 is formed integrally in the cap 23, thereby giving pliancy to the cap 23 for in and out movement when the central button 52 is pressed inward.

The cap 23 may be rotated in the groove 48 and the eccentric mounting of the boss 49 causes the boss to engage the arm 36 at progressively changing distances from the pivot point 31 in the leaf 28. In this way the effective length of the lever arm of the actuating member is changed to adjust the operating travel required of the operating member to snap the leaf from one position to the other. The operating force required to snap the switch will vary substantially inversely with the operating travel.

The cage or frame 24 is held in position by shoulders 53 extending from the inner cylindrical walls of the casting 21, as best seen in FIG. 4; and also by a terminal 54 extending longitudinally from the frame 24 through an opening 56 in the end wall 22.

In the forms shown in the FIGS. 1-5 the mechanism is employed as a double throw switch and to that end a pair of contacts 57 and 58 are mounted respectively on opposite sides of the leaf 28 and engage stationary contacts 59 and 61 respectively formed integral with terminals 62 and 63 respectively, which extend through openings in the end wall 22. The leaf 28 thus constitutes a current-carrying arm of the switch but current need not be transmitted through either of the bearing surfaces at the end of the switch since the serpentine portion 37 formed integral with the leaf 28 constitutes an integral circuit connection which is bonded to the frame 24 at the point 39 and hence to the terminal 54.

In the operation of the switch, inward pressure on the button 52 causes the boss 49 to be pressed inward by virtue of the pliancy of the cap 23, particularly at the corrugation 51. The boss 49 presses the arm 36 to the

left, thereby pivoting the right-hand end of the leaf 28 clockwise in its pivotal mounting 43. This pivoting starts a wave or node traveling from right to left in the leaf. As this node reaches the contact 58 it measurably increases the contact pressure between 58 and 61. As the node passes the contact 58 the pressure becomes greatest and immediately thereafter a sufficient portion of the leaf 28 has been bowed upwardly to cause the leaf to snap to the upper of its bi-stable positions shown in phantom in FIG. 2. This breaks the contact between 58 and 61 with extreme rapidity and makes contact between the contacts 57 and 59. This wave action is similar to that which is more fully described in co-pending application Serial No. 575,467, filed April 2, 1956, now Patent No. 2,964,602 for Snap Acting Mechanism.

When pressure of the button 52 is relieved the bias from the serpentine portion 37 causes the action to be reversed, this time with a rapid snapping away or separation of the contacts 57 and 59.

The cylindrical nature of the casing 21, coupled with the end placement of the terminals 54, 62 and 63, readily adapts the switch shown in FIGS. 1-5 to plug-in use.

In FIGS. 6-9 a modified form of construction is shown wherein the right-hand pivotal mounting of the leaf 28a is effected in a somewhat different manner.

In this form of the invention the frame 24a is continued longitudinally from the free end of the arm 27a with a portion 71 and then returns toward the center of the assembly with a transverse portion 72 finally terminating in a longitudinal section forming the terminal 54a, passing outwardly of the casing through a notch 73 formed in section 21a. Also in this form the case is made rectangular rather than circular and is formed of two longitudinally divided sections 21a and 21b. A notch or slot 74 is formed in the portion 71 adjacent the arm 27a and a complementary slot 76 is formed in the upper surface of the arm 27a immediately adjacent the elongate or bight portion. The two notches 74 and 76 permit the arm 27a to be bent back or forward slightly, thereby to adjust the spacing between the grooves 32a and 43a. This adjusts the compressing and arching of the leaf 28a with corresponding adjustment in the contact pressure and operating force required.

In this form a variation is also made in the leaf 28a in that the stiffening, instead of being effected by a separate piece 41, as in FIG. 5, is done by doubling the leaf itself back and forth upon itself, as shown at 36a. The leaf is then continued downwardly in a U-portion 37a, the end of which is bonded to the transverse portion 72 of the frame 24a.

The leaf 28a is snapped back and forth between its two stable positions by an actuating member 49a mounted for reciprocation transversely of the case by a pair of buttons 75 and 77 sliding in apertures 78 and 79 respectively. A slot or notch 81 is formed midway in the member 49a and brackets the stiffened operating portion 36a of the leaf 28a. Rounded operating bosses 82 and 83 are formed in member 49a on opposite sides of the stiffened portion 36a and engage it to press the leaf 28a back and forth and snap it between its two arched positions.

To permit lateral stacking of switches the base is provided with complementary recess 86 and boss 87.

Where the leaf is ensmalled at the right-hand pivot the two shoulders are bent back as shown at 42a to provide radiused bearing surfaces riding in the grooves 43a. Where the leaf is folded back on itself at 36a the several layers are bonded together as by spot-welding shown at 80.

In the operation of the switch shown in FIGS. 6-9, downward pressing of the button 75 snaps the leaf 28a from its lower to its upper arched position, where it remains until the button 77 is pressed upward, whereupon it returns to its lower arched position.

In FIGS. 10 and 11 there is shown a form of the pres-

ent invention incorporating certain features of both the FIG. 1 and the FIG. 7 forms heretofore described. In these figures the leaf 28d is continued past the pivot trunnion 31d and folded back and forth on itself to form a stiffened portion 36d. The leaf then continues in a downward serpentine portion 37d and is bonded to a base 121 formed integral with the frame 24d. Like the serpentine portion 37 shown in FIG. 2, the portion 37d is springy or resilient like the major portion of the leaf 28d and therefore biases the stiffened end 36d upward.

10 The switch is actuated by a hexagonal button 122 reciprocally mounted in a grommet 123, which is in turn rotatably mounted in a bore 124 formed in the upper wall of the casing 21d. The grommet 123 is formed to provide frictional contact with the case 21d, while allowing free reciprocation of the plunger 122. The plunger 122 has adjacent its lower end an oblique flange 126, which in cooperation with a ledge 127 extending inwardly from the wall of the casing 21d, serves as an upper limit stop for the plunger 122. The opposite edge of flange 126 is stopped by frame arm 27d to limit downward movement of plunger 122. Beneath the flange 126 is a downwardly projecting actuating button 128 which engages the stiffened portion 36d of the leaf 28d so that upon downward 20 pressing of the plunger 122 the leaf is pivoted clockwise about the pivot means 31d and thereby snapped from its lower arched position to its upper arched position, as heretofore described in connection with FIG. 1. The leaf remains in its upper position as long as the plunger 122 is held down. Upon release of the plunger 122 the resiliency of the serpentine portion 37d biases the leaf counter-clockwise and snaps it back to its lowermost arched position.

25 The button 128 is disposed eccentrically with respect to the center line and axis 129 of the plunger 122. Thus, rotatable adjustment of the plunger 122 serves to move the button 128 toward or away from the pivot point 31d; thereby altering the effective lever arm between the contact point of the button 128 and the pivot point 31d. This 30 effects adjustment of the travel stroke required of the plunger 122 with corresponding inverse adjustment of the operating force required.

35 The bore or passage in the grommet 123 through which the hexagonal button plunger 122 extends is of mating 45 hexagonal configuration, so that rotation of the plunger 122 as by a small wrench, also rotates the grommet 123. The upper flange 131 of the grommet 123 is provided with an index mark 132 which cooperates with a series of numbers 133 marked on the case 21d and indicating the 50 button travel required to actuate the switch at that particular angular setting of the plunger 122. The flange 131 is circumferentially ensmalled at 134 to cooperate with a stop 136 on the case 21d to limit angular adjustment of the plunger 122.

55 The angle of the oblique flange or shoulder 126 automatically adjusts the upper and lower stops to suit the length of operating travel selected.

In FIGS. 12 and 13 another form of the present invention is shown, this being a variant of the form shown in 60 FIG. 7 wherein upward arching or bowing of the leaf 28e is effected by the right hand button 76e and return of the arch to its lower position is effected by the left hand button 77e. As noted, the two buttons operate on opposite sides of the pivot point 31e and to that end the stiffened portion 36e of the leaf 28e is extended so as to be substantially symmetrical about the pivot 31e and thereby give a stiffened operating surface for each of the buttons 76e and 77e.

65 The form of the invention shown in FIGS. 12 and 13 permits switch operation, both forward and backward from one side of the casing 21e rather than requiring actuation from both sides, as in the case of FIG. 7.

In the form of the invention shown in FIGS. 14-16 the leaf 28b is not ensmalled laterally to form shoulders 70 constituting the right hand pivot, but instead the leaf

continues straight through past the pivot with a uniform unbroken width, as best seen in FIG. 15. The pivot is formed by a two-part stiffener consisting of an upper plate 91 having a pair of wrap-around wings 29 and lower plate 93 having lateral tabs 94 folded double for added strength and to provide a radiused bearing surface 96. The wings 92 encircle both the leaf 28b and the sheet 93 as shown in FIG. 16.

The resulting assembly not only strengthens the leaf 28b at the point where it will be operated by the operating member 49b, but also clamps in place the tabs or wings 94 constituting the pivot trunnions.

To secure the assembly against longitudinal slipping on the leaf or spring 28b a transverse indentation 97 is formed across the entire assembly.

This form of the invention has an advantage over the previous forms in that there is no inside corner formed in the leaf proper which might form a point of maximum stress and a possible start for fracture.

The actuating member 49b constitutes a button operating through a somewhat springy loop 98, and onto an operating finger 99 bearing against the overlay 91 and sliding in a groove or slot in a ledge 101 formed in the frame 24b.

It will be noted in the form of the invention shown in FIG. 14 that the U-shaped frame 24b is turned at right angles with respect to the leaf 28b from the position of the frames 24 and 24a in the forms previously described; that is to say, in the earlier forms the frame occupied generally the same plane as the leaf 28, whereas in the form shown in FIG. 14 the frame or more specially the bight portion of the frame is spaced from the plane of the leaf 28b. This structure has the advantage that either arm, as for example the arm 27b, may be readily adjusted by being bent at its juncture with the bight portion 24b without the special provision of notches, as described hereinbefore.

As in the form shown in FIG. 1, the return or shunt portion is of the same springy constituency as the leaf 28b with which it is integrally formed, so that it constitutes a return bias urging the spanning portion of the leaf 28b to its downwardly bowed position (FIG. 14).

In FIGS. 17-20 a further form of pivotal mounting is illustrated wherein the trunnions are eliminated entirely and instead a slot or rectangular opening 106 is formed in the straight through leaf 28c and strengthened by a plate 107, the wings 108 of which are bent around the leaf 28c as shown in FIG. 18. A tab 109 is lanced downwardly of plate 107 leaving an opening 111 registering with the opening 106. The tab 109 is bent around the edge of the opening 106 thereby forming a radiused bearing surface 112 which bears against a curved groove 113 formed in a post 27c that extends upwardly from the frame 24c and passes through the opening 106. As in the other embodiments, the leaf 28c is continued integrally in serpentine fashion as shown at 37c to form a return spring and electrical shunt which is riveted to the frame 24c at 114.

As seen in FIG. 20 the openings 106 and 111 are made sufficiently large to pass the post 27c taking into account the bent back tab 109. Notches 116 formed in opposite sides of the wings 108, form a registering opening with the openings 106 and 111 (FIG. 20).

Referring to FIGS. 22-25, another embodiment of this invention is illustrated, wherein a cylindrical case or housing 21' is substantially similar to the housing 21, of the first described embodiment (FIGS. 1-5), with the exception of a pair of oppositely disposed longitudinal grooves 150 provided on the external surface of the housing. A mounting clip 151, having a cylindrical portion 152 and a pair of elongated, rearwardly extending arms 153, may be advantageously used to secure the housing within an aperture 154 of a panel 156 or the like. The aperture 154 is preferably reamed or otherwise drilled to receive the cylinder 21' in a very close fit to reduce vibration.

In order to secure the cylinder 21' within the panel 156, 75

the cylindrical portion 152 of the clip 151 is slipped over the cap 23' to abut shoulders 157 of the housing 21', with the arms 153 extending rearwardly and residing one within each groove 150. The housing 21' is then inserted into the panel 156 and the arms are bent back as indicated at 158 to abut the rear surface 161 of the panel 156 to retain the housing within the aperture 154, and prevent longitudinal movement therein.

The arms are preferably provided with a plurality of oppositely facing notches 159 which provides bevelled edges at the ends of the arms if clipped or cut transversely thereto.

Referring to FIG. 26, a modified embodiment is disclosed wherein a cylindrical band 160 is telescopingly disposed over the housing 21' to abut the rear surface 161 of the panel, and overlie the arms 153 of the clip 151. In this instant embodiment, to secure the housing 21' from longitudinal movement, the arms 153 are bent back over the band 160 as indicated at 162, whereby the flanges 157 are clamped to the panel 156 between the bands 152 and 160. The portions 162 are preferably bent to a position substantially parallel to the arm portions within the grooves 150 and may be trimmed or clipped transversely, as previously described, at a convenient set of notches 159.

Referring to FIGS. 27-30 inclusive, another form of mounting clip is illustrated which is more specifically adapted for mounting the rectangular form of switch, shown in FIGS. 6-8 inclusive, to a panel, or the like, indicated at 170.

The mounting clip, generally indicated by the numeral 171, comprises a unitary length of substantially resilient wire, preferably of stainless steel or the like, which is bent as illustrated to form a pair of spaced, substantially parallel ends or dowels 172 and a pair of oppositely-extending bight portions 173 angularly disposed relative to the dowels 172. The bight portions, together with an interconnecting portion form a generally Z-shaped configuration or, more specifically, interconnected oppositely extending bent portions whose apices or bights extend to opposite edges of the housing.

Each of the bight portion 173 is transversely bent in a plane substantially less than 90° relative to an adjacent end or dowel 172 to form resilient pressure points against the housing 174 when installed, and is preferably of a length suitable for reaching an opposite edge region of the switch housing 174. Pressure is thereby applied at the edges reinforced by the sidewalls 175 of the housing rather than in a central unsupported area thereof, as will hereinafter be described, thus preventing inward distortion of the housing which might otherwise result.

The mounting clip 171 is adapted to secure the housing 174 to the panel 170 by installing the clip in such manner that the ends or dowels 172 extend through apertures 176 provided adjacent diagonally opposed corners of the housing 174 and aligned apertures 177 of the panel, with the bight portions 173 overlying the outer sidewall 178 of the housing. The dowels 172 are preferably of sufficient length to extend substantially outwardly of the face of the panel 170 opposite the switch (as seen in FIG. 28) whereby the ends of the dowels may be grasped as by long-nosed pliers, or the like, to pull the dowels outwardly of the panel with sufficient force to create a pressure of the bight portions 173 on the housing 174. The ends of the dowels 172 are subsequently bent back on themselves to form inwardly-extending tabs 179 (FIG. 29) for securing the housing 174 to the panel 170 while retaining the resilient pressure of the bight portions 173 against the side wall 178 of the housing.

The apertures 176 are preferably located adjacent opposite corners of the housing which are supported by the side walls 175 of the housing 174.

In order to facilitate stacking of a plurality of housings 174 during the installation, the dowel portions 172 are preferably of sufficient length to extend through more than one housing, as illustrated in FIG. 30. Such addi-

tional length of dowel may be cut off to appropriate length if it is desired to mount only one such housing. A unitary mounting clip 171, as described above, advantageously eliminates necessity for screws which require specific lengths for secure installation, and, being unitary, there is nothing to come loose. Furthermore, the Z-shaped configuration provides continual spring tension which compensates for any differential in expansion and contraction and provides added length for greater resiliency which is applicable to portions of the housing which are supported and reinforced by side walls. This instant form of mounting clip also provides a dowel type securement by extending through instead of around the housing.

The recess 86 and boss 87 (FIG. 8) may be eliminated, if desired, when the instant clip 171 is used, since accurate alignment for stacking may be achieved through alignment of apertures 176.

While the instant invention has been shown and described herein in what is conceived to be the most practical and preferred embodiment, it is recognized that departure may be made therefrom within the scope of the invention, which is therefore not to be limited to the details disclosed herein but is to be accorded the full scope of the claims so as to embrace any and all equivalent methods and apparatus.

What is claimed is:

1. Snap-acting switching mechanism comprising: frame means having opposed spaced pivot means, a leaf spring compressed and bowed by the said pivot means thereby to arch said leaf spring into one or the other of two positions, said leaf spring continuing integrally past one of said pivot means, the continued portion of said leaf spring being stiffened by over-lying said continued portion with a sheet of material folded through substantially 180 degrees into position against the continued portion, so that the continued portion is appreciably more rigid than the major portion of the part of said leaf spring spanning said pivot means, said folded sheet of material forming radiused bearing surfaces engaging said one pivot means, and movable operating means for engaging the stiffened portion of said leaf spring and for pivoting the same about said last mentioned pivot means, thereby to effect snapping of the leaf spring from one arched position to the other.

2. Bi-stable electric switch comprising frame means having spaced opposed pivot means, conducting leaf means adapted to carry current spanning said pivot means and being pivoted thereby, said leaf means being compressed between said pivot means to form an arch and being capable of snapping from one position to another, said leaf means extending beyond one of said pivot means, the extending portion of said leaf means being relatively stiffer than the major portion of said leaf means which spans said pivot means, and constituting at least a portion of a circuit connection to a terminal of the switch and integral with said leaf means, and operating means for engaging the extending portion of said leaf means and for flexing said leaf means from one arched position to the other.

3. Bi-stable electric switch comprising frame means having spaced opposed pivot means, conducting leaf means adapted to carry current spanning said pivot means and being pivoted thereby, said leaf means being compressed between said pivot means to form an arch and being capable of snapping from one position to another, said leaf means extending beyond one of said pivot means, the extending portion of said leaf means being relatively stiffer than the major portion of said leaf means which spans said pivot means, and constituting at least a portion of a circuit connection to a terminal of the switch and integral with said leaf means, at least a portion of said circuit connection being resilient and biasing said leaf means toward one of its arched positions, and operating means for engaging the extending portion of said leaf

means and for flexing said leaf means from one arched position to the other.

4. Bi-stable mechanism comprising frame means having opposed pivot means, leaf means bowed and compressed between said pivot means into one or the other of its two arched positions, a portion of said leaf means extending beyond one of said pivot means and being stiffened to form an operating means for the mechanism, an operating member reciprocable substantially normal to the extending portion of said leaf means, means for mounting said operating member for rotation about its axis of reciprocation, said operating member engaging said extending portion at a point spaced radially from said axis, whereby rotatable adjustment of said operating member effects movement of said engaging point toward and away from said one pivot means, thereby to adjust the effective operating lever arm of the mechanism.

5. Mechanism in accordance with claim 4 wherein said operating member comprises a disc-like member disposed concentrically of said axis of reciprocation, an annular portion of said disc-like member being sufficiently flexible to allow the center portion of said member to be flexed inwardly toward said continued portion of said leaf member, said disc-like member having a curved boss spaced eccentrically of said axis of reciprocation and engaging said continuing portion of said leaf member, whereby rotatable adjustment of said disc-like member continuously adjusts the engagement point between said boss and said continued portion, with the point of engagement continuously shifting with respect to said one pivot means, thereby to adjust the effective operating lever arm of the mechanism.

6. Bi-stable mechanism comprising a generally cylindrical housing, pivot means spaced longitudinally within said housing, resilient leaf means spanning and compressed between said pivot means into one or the other of two arched positions, a portion of said leaf means continuing beyond one of said pivot means and being turned at substantially a right angle to said leaf means, an operating member disposed in the end wall of said housing and being mounted for reciprocation along the axis of said housing, said operating member having an operating boss on the inner face thereof engaging said extended portion of said leaf member, said operating member being rotatably adjustable about said axis and said operating boss being disposed eccentric to said axis, whereby rotatable adjustment of said operating member effects adjustment of the operating lever arm of said mechanism.

7. Bi-stable electric switch comprising: frame means having spaced opposed pivot means, first conducting leaf means spanning said pivot means and being pivoted thereby, said leaf means being compressed between said pivot means to form an arch and being capable of snapping from one position to another, and second conducting leaf means in electrical connection with said first leaf means and extending away from one of said pivot means, the extended end of said second leaf means being fixed with respect to said frame means and constituting a terminal of the switch.

8. Bi-stable electric switch in accordance with claim 7 wherein said second leaf means is resilient and biases said first leaf means toward one of its arched positions.

9. Switch in accordance with claim 7 wherein said second leaf means is serpentine in configuration.

10. Switch in accordance with claim 7 having a stationary contact engaged under pressure by a moving contact carried on said first conducting leaf means, said first conducting leaf means having a length-to-thickness ratio such as to cause, during operation of said switch, a continuous increase in said pressure until said snapping occurs.
